JAMES KAY, OF SALEM, INDIANA.

Letters Patent No. 83,507, dated October 27, 1868.

IMPROVEMENT IN WHEEL-PLOWS.

The Schedule referred to in these Letters Patent and making part of the same.

To all whom it may concern:

Be it known that I, JAMES KAY, of Salem, Washington county, in the State of Indiana, have invented a new and improved Wheel-Plow; and I do hereby declare that the following is a full, clear, and exact description thereof, reference being had to the accompanying drawings, making part of this specification, in which—

Figure 1 is a plan view of the improved plow.

Figure 2 is a longitudinal section taken in the vertical plane indicated by the course of red line *x x* in fig. 1.

Figure 3 is a transverse section taken in the vertical plane indicated by red line *y y*.

Figure 4 is a similar view of the same parts shown in fig. 2, representing the plow elevated.

Similar letters of reference indicate corresponding parts in the several figures.

This invention relates to an improvement in wheel-plows, and is designed to afford a substantial single-riding turn-plow, which can be successfully used in turning gravelly soil, and easily managed by the feet of a person riding upon the carriage to which the plow is applied.

The nature of my invention consists in a novel manner of bracing the beam of a turn-plow, and securing such beam to a vibrating frame upon a two-wheel carriage, said frame being hinged to hounds in front of the axle of the carriage, and provided with means whereby it can be adjusted so as to have the plow run at any desired depth in the ground, as may be required.

Provision is also made for allowing a person, mounted in a seat upon the axle of the said carriage, to raise the plow clear of the ground, or to depress and hold the plow down during the operation of turning the soil.

Provision is also made for sustaining the double-tree by means of braces or holdback-rods connected to the plow-beam, and also to the axle-tree, all as will be hereinafter described.

To enable others skilled in the art to understand my invention, I will describe its construction and operation.

In the accompanying drawings, *A A* represent two transporting-wheels, applied upon an axle, *A'*, from which latter the hounds *B* project, to which the draught-pole *B* is secured. The axle *A'* has a metallic plate secured upon it, and the hounds are braced to the axle by means of metallic straps *a*, which are applied to them, as shown in the drawings.

C represents a rectangular open frame, composed of two transverse beams secured firmly to the ends of three longitudinal beams. This frame is hinged at its front end to the hounds *B*, by means of eye-bolts *b*, so that the rear end of this frame can be raised and depressed. This frame *B* is supported upon the axle *A'*, by means of screw-rods *c c*, which are tapped through the two outside longitudinal bars, and by means of which the rear end of this frame can be ad-

justed so as to be supported upon the axle, at any desired height. The studs *b' b'*, which are inserted into the upper side of the axle, perpendicular to it, are designed to serve as side-stays and guides for keeping frame *C* in its place against lateral thrust.

D represents a seat for the driver, which is supported upon the axle *A'*, and mounted upon standards *c' c'*, which are bolted to said axle. Below this seat *D*, and secured to the axle *A'*, are two brackets, *d d'*, which incline backward, and have two foot-levers or treadles pivoted to them, as shown in the drawings. The treadle *e*, on the right-hand side of the central beam of frame *C*, is connected to an inclined plow-beam, *C'*, by means of a rod, *e'*, and is designed to afford a means whereby a person sitting upon the seat *D* can, with his foot, raise the plow *E* from its work. The lever or treadle *f* is connected to said plow-beam by means of a rod, *f'*, and is designed to afford means for enabling the person to hold the plow *E* and frame *C* down to the work. It will be seen, by reference to figs. 2 and 4, that a rod, *g*, is employed as a means for holding down and staying the bracket *d'* against upward thrust during the act of holding the plow down to its work by pressing with the foot upon treadle *f*.

The plow-beam *C'* is mortised into the central longitudinal beam of frame *C*, and inclined backward. This beam is also secured to the frame *C* by means of two lateral braces, *h h*, two front braces, *i j*, and a rear brace, *k*, which system of bracing allows me to employ a beam, *C'*, long enough to admit of its being successfully secured to the elevated carriage-frame *C*.

The plow *E* may be constructed like any well-known turn-plow. It is secured to the beam *C'* by means of braces, *l j*, and its mould-board is strengthened by means of a lateral brace-rod, *m*, which is secured to said mould-board at one end, and to the frame *C* at the opposite end. The brace-rod *j* has an eye formed on its lower end, through which a bar, *n*, passes, that is rigidly secured to the plow *E*. This rod *j* passes up through a portion of the plow-beam, and through the central beam of the frame *C*, and receives a nut upon its upper end, by means of which the plow is drawn tight and held firmly. The bar *n* is screwed to the back of the mould-board at one end, and its opposite end enters a hole made through the landside-plate of the plow. When it is desired to remove the plow from its beam, the bar *n* is first detached.

The brace-rod *j* serves as an auxiliary plow-beam, and also as a brace to assist in strengthening this beam against backward strain and movement.

The braces which I have described are all so arranged that they do not interfere with the movements of the frame *C*, in the operation of plowing. These braces also serve to distribute the strain upon the beam *C'*, equally upon said frame *C*, so that a comparatively light frame-work can be employed.

The double-tree G, which is secured at the middle of its length to draught-pole B', and to which the single-trees are attached, is braced and strengthened by means of the rods or chains *p p*, attached to its ends, and also to the axle-tree A', as shown; also, by means of the inclined rod *s*, which is attached to the plow-beam C', at one end, and to a short link, *t*, at the other end, as shown in figs. 2 and 4. This short link, *t*, is secured fast to the draught-pole by means of the bolt which secures the double-tree to said pole, and it serves as a forward-jointed attachment for the rod *s*, which will allow the frame C to vibrate.

The coulter, *J*, is a curved blade with a short hook on its rear upturned end, which hook will be embedded into the side of the beam C', when this coulter is screwed tightly in place to the landside of said beam.

From the above description it will be seen that I have a plow which can be readily managed by a person sitting upon the seat D, on the carriage-axle A'; and that such person will have his hands free to handle the reins and control his team. I secure the plow-beam or standard C' to the frame C in such manner that no ordinary resistance will break or derange any of the parts; I sustain the plowshare against strain; I provide for enabling the attendant to set the plow to run at any desired depth; I enable the driver to press the plow down to its work, and to raise the plow free from the ground at pleasure; and I make provision for causing the horses to draw from the axle and plow-standard; all of which features, combined in the manner shown, make a very complete implement which can be readily controlled.

Having described my invention, What I claim as new, and desire to secure by Letters Patent, is—

1. A two-wheel single-riding plow, having the plow E and its standard C' secured to a hinged frame, C, as described, in combination with lateral, front, and rear braces arranged for sustaining said standard, substantially as described.

2. The brace-bar *j*, connected to the bar *n* of the plow E, passed through the standard C', and secured to the frame C, substantially as described.

3. The combination of levers, or treadles *e f*, with a plow which is applied to a hinged frame, C, upon a two-wheel carriage, one of which levers or treadles is adapted for raising the plow and its frame, while the other is adapted for depressing said parts, substantially as described.

4. The brace *g*, connected to the bracket *d*, and the seat-standards *c*, substantially as and for the purposes described.

5. The adjusting-screw rods *c c*, applied to the hinged frame C, and supporting this frame upon the axle A' of a single-riding plow, substantially as and for the purpose described.

6. In a machine which is constructed as described, the three holdback-rods or chains *p p s*, attached to the double-tree, substantially as and for the purposes described.

JAMES KAY.
